UNITED STATES PATENT OFFICE.

HOWARD K. CLOVER, OF LOS ANGELES, CALIFORNIA, ASSIGNEE, BY MESNE ASSIGNMENTS, TO CLOVER ELECTRICAL CORPORATION, A CORPORATION OF NEVADA.

ELECTRICALLY-HEATED FAUCET.

1,313,519.

Specification of Letters Patent. Patented Aug. 19, 1919.

Application filed June 18, 1918. Serial No. 240,576.

To all whom it may concern:

Be it known that I, HOWARD K. CLOVER, a citizen of the United States, residing at Los Angeles, in the county of Los Angeles 5 and State of California, have invented new and useful Improvements in Electrically-Heated Faucets, of which the following is a specification.

This invention relates to improvements in 10 electric heaters of the faucet type such as embodied in my patent for electric water heater, issued January 8, 1918, No. 1,252,661.

The primary object of the invention is to incorporate with a faucet an electric 15 heater and to provide an electrically heated faucet of such construction and arrangement that water or the like as it passes through the faucet, will be effectively heated.

Another of the objects of the invention is 20 to provide a faucet of the above-mentioned character in which the heating element may be readily removed and replaced without necessitating a complete disassembling of the faucet.

25 Another object is to provide an electric water heater with which water or the like may be heated to different temperatures at will.

Another object of the invention is to provide 30 an electrically heated faucet in which the circuit controlling means for the heating element is apart from the valve and heating element and is not subject to injury due to the possibility of water or moisture 35 coming into contact with the controlling means.

The invention further consists in the novel 40 and useful provision, formation, combination, relative arrangement of parts, members and features, all as hereinafter described, shown in the drawings and finally pointed out in claims; all taken in consideration with simplicity and inexpensiveness in construction and organization, together with 45 facility in assemblage or disassemblage and adaptability to various working conditions. Other objects and advantages will appear during the course of the following description:

50 In the drawings:

Figure 1 represents a vertical sectional view taken on line x^1-x^1 of Fig. 3 of an electrically heated faucet constructed in accordance with my invention;

Fig. 2 represents a horizontal sectional view taken on line x^2-x^2 of Fig. 1;

Fig. 3 represents a top plan view;

Fig. 4 represents a cross-sectional view taken on line x^4-x^4 of Fig. 2;

Fig. 5 represents an enlarged cross-sectional view taken on the line x^5-x^5 of Fig. 2;

Fig. 6 represents a vertical sectional view of the valve;

Fig. 7 represents a cross-sectional view of 65 the valve, being taken on line x^7-x^7 of Fig. 6;

Fig. 8 represents a detail plan view of the auxiliary valve;

Fig. 9 represents a fragmentary detail side 70 elevation of a modified form of valve showing a part broken away and the valve seat in section;

Fig. 10 is a cross-sectional view taken on the line $x^{10}-x^{10}$ of Fig. 9; and

Fig. 11 is a detail top plan view of the heating element holder.

Referring particularly to the drawings, A designates as an entirety a faucet provided with a body B, spout C, valve D, valve 80 handle E, heating element housing F, connection member G of the housing, circuit controlling means H associated with the housing, guard means J coöperating with the controlling means, auxiliary means K controlled by movement of the valve D, safety valve L in the housing G, and heating element M mounted in the housing F therefor. These elements constitute the essential features of the invention and their particular 85 construction in each case will be later more fully described.

The body B of the faucet is in the form of a casting and is preferably annular, although it may be of any suitable shape. 90 This body is formed with a central valve seat 1 which is of substantially cylindrical form and depending from the periphery of the body is an annular flange 2. The spout C projects outwardly from the periphery of 100 the body and communicates with the passage 3 formed through the body and wall of the valve seat 1. The valve D is tapered downwardly and the seat 1 therefor is correspondingly tapered. A passage 4 is formed 105 in the valve D and extends vertically from the bottom of the valve upwardly to a point midway of the ends thereof and then

branches outwardly laterally into hot and cold water passages 5 and 6 respectively, each lateral branching passage opening through the side of the valve and adapted 5 for registration with the passage 3 and spout C. The hot water passage is restricted at its discharge end and is considerably smaller at this point than the entrance end of the passage 3 so as to prevent a rapid flow 10 of liquid from the valve to the passage, whereas the cold water passage 6 is substantially the same size as the passage 3 and permits a relatively greater flow of liquid when in registration with said passage. 15 The discharge ends of these passages are spaced so that either may be brought into registration with the passage 3. The upper end of the valve D is annularly recessed as at 7, and has a stem 8. A helical expansion 20 spring 9 is mounted within said recess, surrounds the stem 8 and abuts the inner face of a flange cap 10, which cap is internally screw-threaded and turned upon a screw-threaded upper end of the valve seat 1. The 25 stem 8 extends upwardly through the cap 10 and is reduced as at 11 near its upper end, said reduced portion extending through the opening 12 in the center of the handle E. The extreme upper end of the valve is again 30 reduced as at 13 and screw-threaded to receive a screw cap 14 which holds the handle in place. The spring 9 tends to force the valve D downwardly and holds the valve securely in its seat in such manner that no 35 packing is needed to prevent leakage.

The housing F comprises a cup-shaped body portion 15, the sides of which are recessed exteriorly and screw-threaded as at 16 adjacent their upper edges so as to receive the screw-threaded flange 2 of the body B and to dispose the outer faces of the flange and sides of the body 15 in flush relation. The body B and housing F provide a chamber which shall be generally designated N 40 and hereinafter referred to as the heating chamber. The valve seat 1 extends into this chamber for a considerable distance. The connection G is in the form of an exteriorly screw-threaded boss 17 and is provided with 45 a central passage 18. This boss or connection is secured to a water or fluid pipe, not shown, by having threaded engagement therewith and the passage 18 through the connection communicates with the heating chamber N. Intermediate the ends of the 50 passage 18 there is provided a valve seat 19 for the valve L. This valve is supported upon a spider 20 and has a stem 21 which extends upwardly through the passage and 55 into the heating chamber N. An expansion spring 22 is mounted upon the valve stem and interposed between the valve and the spider 20, said spring at all times tending to urge the valve upwardly. The valve is held 60 in open position, however, by engagement of

the stem 21 with some portion of the heating element as will be later more fully described. Upon the removal of the heating element the valve L will close under the action of the spring 22 and pressure of the 70 water in the passage 18. The closing of this valve is necessary in order to prevent waste of water when disassembling the faucet.

As a means for permitting the passage of water in a relatively large volume to the 75 chamber N and from thence through the valve to the spout C there is provided a passage 23 which is formed in the body 15 of the housing F in the bottom wall of said housing. This passage communicates with the 80 passage 18 in the connection G at a point between the upper end of the passage 18 and the valve seat 19, and also communicates with a vertical passage 24 which is an extension of the passage 23 in the side wall of 85 the body 15. The passage 24 terminates in an opening formed through the upper side of the wall 15 and is communicated with the heating chamber N through a port 25 formed in the auxiliary valve K. This port 25 is 90 preferably T-shaped, the head lying in registration with the passage 24 and the stem thereof providing for communication of the passage 24 with the chamber N.

The valve K comprises a substantially 95 horizontal and flat ring plate 26, which is slidably mounted upon the upper edge of the side wall of the body 15 and has an inward extension which terminates at a point adjacent to the seat 1, and is then directed 100 downwardly as at 27 and then inwardly laterally terminating in a ring-like portion 28 which is suitably secured to the lower end of the valve D. In this connection it will be noted that the valve D extends below the 105 lower end of the seat and is reduced as at 29 so as to receive the portion 28. The connection of the valve K with the valve D is for the purpose of operating the valve K simultaneously with the operation of the 110 valve D, and it will be noted that when the valve D is closed the valve K is open, whereas when the valve D is opened the valve K is closed. However, it is possible to open the valve D slightly and likewise only partially close the valve K. The particular operation and advantage of this arrangement will be later more fully described. To protect the valve D from shrinkage or improper seating, due to the action of heat, the inner 115 face of the body B is lined with insulation material 30. A preferably annular and cup-shaped heating element holder 31 is mounted within the chamber N. This holder 31 is provided with two concentric walls 32 and 120 33 between which is provided the main portion of the chamber N and the element M is mounted. This holder may be described as an annular cup receiving the heating element and said member is constructed of 125 130

- insulation material so as to prevent the metal of the faucet from becoming heated to too great an extent. The holder 31 engages the stem 21 of the valve L so as to hold said valve open, and upon the removal of the holder 31 the valve will be closed by the action of the spring, shutting off the supply of water to the chamber N and avoiding waste. The bottom wall of the body 15 is counter-bored or recessed as at 34 so as to provide a passage or interspace 35 through which liquid passes from the passage 18 into the chamber N. The bottom wall of the holder 31 is provided at points 15 between the walls 32 and 33 with openings or perforations 36 which establish communication of the inter-space 35 with the chamber N. The upper edge of the wall 33 is spaced from the insulation lining so sufficiently to provide the passage 37, which passage communicates the chamber N with an annular passage 38. The passage 38 is substantially L shaped and is provided by the spacing of the wall 33 from the valve seat 25 1 and the spacing of the valve seat from the bottom of the holder 31.
- The heating element M is in the form of a helical annular coil of some suitable high resistance wire and its ends are connected 30 respectively with terminal members 39 and 40. These terminal members extend from the underside of the body 15 into the chamber N for connection with the heating element and are connected by conductors 41 35 with the circuit controlling means or closer H. The housing F includes as an integral part of the body 15 an extension 43 of said body which provides a chamber 44 for housing the means H and J. Mounted within 40 this chamber 44 is an insulation body member 45 which supports four upright contact members 46 of the circuit closing means. These contact members are secured in place by bolts 47 and 48. The contact members 45 are arranged in pairs opposite to one another and the conductors 41 and 42 are connected with the bolts 47 which hold the contact members 46 nearest to the body 15, whereas conductors 49 and 50 which lead 50 from a suitable source of electrical energy, not shown, are connected with the bolts 48 for holding the other contacts 46. A horizontal switch bolt 51 is slidably mounted upon a base 52 formed on the body 45 and 55 extends outwardly through openings 53 formed on opposite sides of the walls of the extension 43. In this connection it will be noted that the extension is preferably of rectilinear outline. On the ends of the bolt 60 51 are mounted buttons 54 and 55 being respectively the "on" and "off" buttons. The bolt 51 is mounted for reciprocation and carries transverse arms 56 and 57, there being contact members 58 on the ends of the arms, said contact members being adapted for contact with the contacts 46, and the arms 56 and 57 are preferably of spring material so as to insure positive engagement of the contacts. Movement of the switch bolt 51 in one direction caused by pushing 70 in the "on" button 54 will cause the contacts 58 to engage the contacts 46 and close the circuit. Movement opposite to this of the bolt 51 caused by pushing in the "off" button 55 will move the contacts 58 out of engagement with the contacts 46 and break the circuit for the heating element M.
- The means J is provided for guarding against operation of the circuit closer H when the valve D is in closed position. This 80 means comprises an L-shaped locking plate 59 which is mounted in the housing 43 in such manner as to prevent the button 54 from being pushed inwardly, that is, the circuit from being closed. This plate 59 is 85 carried upon a vertically disposed pin 60 which is extended through an opening 61 in the insulation base 45 and is provided with a head 62 engaging said base. The pin extends upwardly through the chamber 90 44 and a closure plate 63 which is mounted upon the extension 43 and held in place by suitable fastening elements 64. The upper end of the pin is rounded as at 65 and is normally disposed at a point above the level 95 of the closure plate 63. A helical expansion spring 66 is mounted upon the pin 60 and abuts the plate 59 at its upper end and the switch bar 51 at its lower end. There is provided a slot 67 in said switch bar for the 100 reception of the pin 60. In this connection it will be noted that the switch bar is provided with slots 68 near its ends and fastening elements 69 are inserted through the slots and body 45 to secure the switch bar 105 in place. The plate 59 is so positioned upon the pin 60 that the shorter leg 59^a thereof is adapted for coöperation with a screw 99 which is provided for holding the arm 56 upon the bar 51 and passes through said 110 arm, and insulation material 70, which latter is interposed between the arm 56 and switch bar. There is provided another such screw 99 for securing the bar 57 in place. As shown in Fig. 5 of the drawings in full lines the switch is in "on" position and the locking plate 59 is in "up" position so that the screw 99 will clear the leg 59^a of the L-shaped bar 59 when the switch is moved to off position. At this time, as will be later 115 more fully described, the leg 59^a is moved downwardly to a point rearwardly of the screw 99 and serves to prevent movement of the switch bar and supported parts, into position so that the circuit will be closed. 120 The valve handle E is provided with a rearward and downwardly curved extension 72 and the free end of this extension is provided with a cam head 73, which, when the valve handle is moved into position to close 125

the valve D, will engage the rounded upper end 65 of the pin 60 and force said pin together with the locking plate 59 downwardly against the action of the spring 66 so that the leg 59a of the locking plate will be disposed back of the screw 99 and prevent movement of the switch bar into "on" position. When the valve handle is moved into "on" position the head 73 moves from engagement with the pin 60 and the spring 66 then forces the pin 60 and locking plate 59 into "up" position, freeing the locking plate and allowing the switch to be moved into "on" position.

15 In the operation of the faucet assuming that the valve D is closed and the parts are in the positions shown in Figs. 1, 2 and 3 of the drawings, the extension 72 of the handle E is in such position that the head 20 73 holds the pin 60 depressed and the locking plate 59 in locking position so that it will not be possible to close the circuit for the heating element.

By turning the valve handle to the left 25 so that it is over the designation "Hot" which is stamped or otherwise appears upon the body B of the faucet, the valve D is opened and the hot water passage 5 brought into registration with the passage 3 of the 30 spout C. The water or other fluid will readily flow from the chamber N through the passage 37 at the upper side of the chamber, passage 38 and central valve passage 4 of the hot water valve passage 5.

35 In this connection it will be noted that the heating element and chamber are under the pressure of the water or other liquid supplied thereto, at all times. The liquid enters the faucet through the connection passage 18 and passes therefrom through the 40 passage 35 in the bottom of the housing F, openings 36 in the bottom wall of the heating element holder 31, and into the chamber N. From the chamber N the liquid 45 passes through the passages 37 and 38 and up through the passage 4 of the valve D. It will thus be seen that the water pressure of the feed pipe is maintained in the faucet at all times. In addition to this, when the 50 valve D is closed the auxiliary valve K is opened and liquid passes through the passages 23 and 24 and the valve port 25 into the chamber N.

Assuming that the valve D is open, as 55 above described, the head 73 of the handle extension 72 has moved from engagement with the pin 60 and the latter together with the locking plate 59 are in "up" position as shown in Fig. 5 of the drawing. The operator may then close the circuit for the heating element M by pushing the button 54 inwardly. This action moves the contacts 58 into engagement with the stationary contacts 46, and in this way closes the circuit.

When the circuit for the heating element is 65 closed the heating of the water takes place immediately and as the water is under pressure within the chamber N and the hot water passage 5 is restricted or smaller than the central valve passage 4, the velocity of the 70 water flowing through the faucet will be slower than that flowing through the spout, and in this way the water is retained in the heating chamber sufficiently long to provide for a thorough heating thereof. By turning 75 off the heating element cold water will run through the faucet and it will be seen that hot or cold water may be had at will by a proper manipulation of the switch. If desired, the handle E may be moved to the 80 right so as to bring the cold water passage 6 of the valve into registration with the spout passage 3. This provides for a larger volume of water to discharge from the faucet. The switch may be closed so as to 85 operate the heating element at this time as well as when the hot water outlet is in registration with the spout. At the time that the handle E is moved to open the valve the 90 valve K is correspondingly moved and when the valve D is opened to its full extent by movement of the handle in either direction, the valve K closes, that is, the port 25 in said valve moves completely out of registration with the passage 24. When the valve D 95 is partially open the valve K is only partially closed and water is allowed to pass through the passages 23 and 24 and the valve port 25 into the chamber N. In this way the water heated in the chamber N will 100 rise, pass through the valve port 25 and passages 24 and 23 into the passage 18 which leads to the chamber N by way of the passage 34 and openings 36. The provision of this circulation of water is highly 105 desirable in order to provide for an expeditious heating of the water without the possibility of burning out the heating element or otherwise injuring the faucet. By varying the degree of opening of the valve D the 110 temperature to which the water will be heated may be correspondingly varied and in this way water may be heated to any desired temperature.

The disassembling of the faucet for the 115 purpose of renewing the heating element or for the purpose of inspection or repair, may be readily accomplished by unscrewing the body B from the housing F. When this is done the holder 31 for the element M is removed, together with said element, after the removal of the bolts 39 and 40. Upon removal of the element 31 the valve stem 21 is freed and the valve L moves upwardly under the action of the spring 22 and water pressure so that said valve is closed and waste of water is prevented.

Referring to Figs. 9 and 10 wherein there

- is illustrated a modified form of valve, 74 designates the valve as an entirety and 75 the seat for said valve, there being provided a spout 76 communicating with the seat.
- 5 This form of valve is downwardly tapered and instead of being formed with a passage-way in the form of an opening therethrough is provided with grooved channels 77 and 78 for cold and hot water respectively. These
- 10 channels are formed by grooving or recessing the valve longitudinally upon the outer face thereof and the channels are formed such distance apart that one may register with the spout 76 while the other is out of
- 15 registration with said spout. The channel 78 for hot water is smaller than the channel 77 so that the flow of water will be lessened when the channel 78 is in registration with the spout and water will flow into the faucet
- 20 at a greater rate than out of it in order that an effective and expeditious heating may be provided.

It is to be understood that I may make minor changes in the details of construction, size and proportion of parts of the invention, without departing from the true spirit and scope thereof as defined in the appended claims.

Having thus disclosed my invention, I claim and desire to secure by Letters Patent:

- 30 1. In an electrically heated faucet, a housing having a discharge opening, a valve to control the flow of fluid from said housing, said housing having a fluid intake, electric heating means in said housing, a slidably mounted circuit closer controlling the supply of electrical energy to said heating means, means for operating said valve and means locking said circuit closer against
- 35 40 sliding movement when the valve is closed, said last named means permitting operation of the circuit closer upon the opening of the valve.
- 45 2. In an electrically heated faucet, a housing having an intake and an outlet for fluid, a valve controlling the passage of fluid from said housing, electric heating means in said housing, a circuit closer for controlling the supply of electrical energy to said heating
- 50 55 means and including a slidably mounted reciprocating bar, means for operating the valve, and means operated by movement of the valve operating means to prevent sliding of the circuit closer when the valve is closed and which permits sliding of the circuit closer when the valve is open.
- 60 3. In an electrically heated faucet, a housing having an intake opening and a discharge opening, a valve to control the flow of fluid from said housing, an electric heating element mounted within the housing, means to control the supply of electrical energy to said heating element, means for operating said valve, said housing having a
- 65 by-pass passage formed therein communicating at its ends with the intake opening and interior of the housing to provide for a circulation of fluid within the housing.
- 70 4. In an electrically heated faucet, a housing having an intake opening and a discharge opening, a valve to control the flow of fluid from said housing, an electric heating element mounted within the housing, means to control the supply of electrical energy to said heating element, means for operating said valve, said housing having a by-pass passage formed therein communicating at its ends with the intake opening and interior of the housing to provide for a circulation of fluid within the housing, and a valve for controlling said by-pass.
- 75 5. In an electrically heated faucet, a housing having an intake opening and a discharge opening, a valve to control the flow of fluid from said housing, an electric heating element mounted within the housing, means to control the supply of electrical energy to said heating element, means for operating said valve, said housing having a by-pass passage formed therein communicating at its ends with the intake opening and interior of the housing to provide for a circulation of fluid within the housing, and a valve for controlling said by-pass; said
- 80 85 90 95 100 105 110 115 120 125 last named valve being connected with and operated by movement of the first named valve.
6. In an electrically heated faucet, a housing having an intake opening and a discharge opening, a valve to control the flow of fluid from said housing, an electric heating element mounted within the housing, means to control the supply of electrical energy to said heating element, means for operating said valve, said housing having a by-pass passage formed therein communicating at its ends with the intake opening and interior of the housing to provide for a circulation of fluid within the housing, and a valve for controlling said by-pass; said last named valve being connected with and operated by movement of the first named valve and arranged to open said by-pass when the first named valve is closed and acting to close said by-pass upon movement of the first named valve to open position.
7. In an electrically heated faucet, a housing having an intake and an outlet for fluid, a valve controlling the passage of fluid from said housing, electric heating means in said housing, a circuit closer for controlling the supply of electrical energy to said heating means, means for operating the valve, means operated by movement of the valve operating means to prevent operation of the circuit closer when the valve is closed and which permits operation of the circuit closer when the valve is open, a valve for control-

ling the passage of fluid into said housing, said valve being held open by the housing when the same is assembled, and spring means at all times tending to close said valve whereby when the housing is disassembled the valve will be automatically closed.

8. In an electrically heated faucet, a housing in sections detachably secured to one another, one of the housing sections having a fluid intake, the other of said sections having a fluid outlet, a heating element mounted in the housing, a valve controlling the discharge of fluid from the housing, means to control the supply of electrical energy to said heating element, an insulation member mounted in the housing and receiving the heating element, a valve for controlling the intake of fluid and being normally held open by said insulation member, and means for closing the valve, acting upon removal of the insulation member.

9. In an electrically heated faucet, a hous-

ing in sections detachably secured to one another, one of the housing sections having a fluid intake, the other of said sections having a fluid outlet, a heating element mounted in the housing, a valve controlling the discharge of fluid from the housing, and means to control the supply of electrical energy to said heating element; said valve being carried by the first named housing section, and a valve carried by the last named section and controlling the intake of fluid relative to the housing, said last named valve being normally held open, and means acting when the housing is disassembled to close said last named valve.

In testimony whereof I have signed my name to this specification in the presence of two subscribing witnesses.

HOWARD K. CLOVER.
